UNITED STATES PATENT OFFICE.

JOHN C. BLAND, JR., OF SEWICKLEY, PENNSYLVANIA.

VAPORIZER FOR EXPLOSIVE-ENGINES.

SPECIFICATION forming part of Letters Patent No. 682,905, dated September 17, 1901.

Application filed May 20, 1901. Serial No. 61,047. (No model.)

To all whom it may concern:

Be it known that I, JOHN C. BLAND, Jr., a citizen of the United States, residing at Sewickley, in the county of Allegheny and State of Pennsylvania, have invented certain new and useful Improvements in Vaporizers, of which the following is a specification, reference being had therein to the accompanying drawings, forming part of this specification,

10 in which—

Figure 1 is a central vertical sectional view through my improved vaporizer. Fig. 2 is a horizontal sectional view on the line II II of Fig. 1. Fig. 3 is a sectional view on the line 15 III III of Fig. 1. Fig. 4 is a similar sectional view on the line IV IV of Fig. 1. Figs. 5 and 6 are views similar to Fig. 1, but illustrating modified constructions.

My invention relates to devices for vaporizing hydrocarbon and other liquid fuels; and it consists in means for disintegrating and commingling the liquid fluid with proper proportions of air in order to deliver the mixture to an explosive motor or other consuming device, and the invention relates to means for such purposes and also to means for regulating and controlling the supply of fluid and air, respectively.

Referring to the drawings, 2 represents the 30 case, with which is incorporated the other elements of the invention, the case having at its upper portion an attached liquid-fluid-supply connection 3, opening into the chamber 4, containing the needle-valve 5, by which the supply of fluid may be accurately controlled. In the construction shown in Fig. 1 the seat 6 for the valve is formed in the upper portion of a downward-extending hollow stem 7, which terminates in a conical hood 8, which hood is 35 surrounded by a downwardly-extended shell 9, formed integrally with or attached to the top 10 of the case. The case and likewise the shell are preferably circular in cross-section, and between the shell 9, which extends only partially into the interior of the case 2 and the sides of the case 2, is an intervening space 11, into which the commingled fluid and air will rise after emerging from the lower end of the shell 9.

50 Within the conical hood 8 is a cone 12, the point of which extends upwardly to the lower end of the hollow stem 7, and which is adapt-

ed to receive the downward-dropping fluid, which will spread out over the cone 12 in a thin covering of liquid upon the outer surface of the cone, from the lower edge of which it will drop upon the sides of a downwardly-extended dome 13, of fine wire-gauze, which projects downwardly to within the interior of the lower portion of the shell 2. The gauze 60 may, however, be of other form or construction, as will be readily understood. The cone 12, hood 8, shell 9, and dome 13 are secured together in any suitable manner at the lower edge of the shell, so that their relation to each other will remain fixed, and as thus constructed it will be seen that there is provided between the inner surface of the cone a narrow coniform space 14, so that the downwardly-dropping fluid may either flow upon 70 the upper surface of the cone or upon the inner surface of the hood and in either case will be delivered at the lower peripheral extremity of the shell 9, from whence it will fall into and upon the inner sides of the wire-gauze dome 13. In place of making the wire-gauze covering dome-shaped it will be understood that any other form may be utilized which will give good results. Through the lower portion of the walls of the hood and of 80 the cone are provided perforating-openings 15 16, preferably in register with each other, and in the upper portion of the top 10, within the periphery of shell 9, are provided one or more air-inlet openings 17, through which air 85 may enter, and such air will pass through openings 15 and 16 to the interior of dome 13, and in such action will take up or absorb a certain portion of the liquid fluid, which as thus charged or suspended in the air will be 90 carried by it into the interior of the case 2 and from thence outwardly to the delivery-opening 18 to the motor or other point of consumption. For the purpose of more thoroughly commingling the air and fluid, either 95 or both openings 15 16 may be covered by thin gauze 19, as indicated, and it will be understood that these openings as well as their size may be regulated and adapted to the particular purposes in view.

Through the upper portion of the case 2 extends one or more perforated openings 20 for the purpose of admitting a diluting current of air. For the purpose of accurately regulating

such supply any suitable cut-off mechanism may be used, as a ring 21, provided with corresponding openings 22, which ring may be rotatably mounted upon the case, so that the supply of air may be accurately controlled or entirely shut off, as may be desired. At its lower portion the case 2 is provided with a drain-cock 23, by which any excess of fluid not taken up by the air may be drained away, and it will be observed that by the location of the outlet-opening 18 at the upper portion of the case the device as so arranged provides for the collection of any excess or unabsorbed liquid, and likewise insures the regularity of the mixture-supply to the motor.

In the construction shown in Fig. 5 the hood 8 is dispensed with, the valve-seat 6 being merely screwed up into the top 10 and valve-case 4, while a cone 12 is alone mounted in the interior of the shell 9 and is adapted to receive the downward-dropping liquid and to spread it out in a thin film and to discharge it upon the interior of the gauze dome 13. The gauze-covered openings 16 are also provided, and the case is in every respect the same, the operation of the absorption by the incoming air and the circulation of the mixture being substantially the same as already described. I have, however, provided a short tube 7' to insure the accurate dropping of the liquid upon the point of the cone.

In the construction shown in Fig. 6 the cone 12 is dispensed with and the hood 8 retained, the liquid in such case dropping downwardly upon the interior walls of the hood, spreading out thereon in a thin film, and being discharged upon the inner side of the gauze dome. The openings 15 may likewise be covered with gauze, as shown, and the construction of the device otherwise as well as its operation, the circulation of the incoming and outgoing currents of air and mixture being the same as I have already described.

I am aware that perforated cones have been employed in devices for the general purpose of vaporizing liquid fluids, and am familiar with the patent issued to B. W. Grist, No. 545,125, but believe I am the first to make a vaporizer in the manner shown and described.

The advantages of my invention will be readily appreciated by those familiar with the use of fluid motors or those utilizing liquid fluid in any case where it is desirable to finely commingle and charge the same in an air-supply. It is very simple in construction, economical, and not liable to get out of order, and very efficient in use, and capable of accurate adjustment.

Various changes and modifications may be made in the size, design, proportions, or arrangement of the parts or other details of construction by the skilled mechanic without departing from my invention, and I do not desire to be limited to the exact construction shown, but to include all such changes and variations within the scope of the following claims.

Having described my invention, what I claim is—

1. A device for vaporizing liquids, comprising an outer casing, a downwardly-extending shell therein, an inverted-dome-shaped wire-gauze covering for the bottom of the shell, a coniform distributer within the shell, and a liquid and an air supply above the distributor, substantially as set forth. 70

2. A device for vaporizing liquids comprising an outer casing, a downwardly-extending shell therein, a wire-gauze covering across the bottom of the shell, an upwardly-extending 80 coniform distributer within the shell and attached thereto at its lower edge, and a liquid and an air supply above the distributer, substantially as set forth.

3. A device for vaporizing liquids, comprising an outer casing, a downwardly-extending shell therein, a gauze covering across the bottom of the shell, an upwardly-extending coniform distributer within the shell and attached thereto at its lower edge, a liquid-supply and 90 an air-supply above the distributer, and an outlet-opening in the side of the case, substantially as set forth. 85

4. A device for vaporizing liquids, comprising an outer casing, a downwardly-extending 95 shell therein, a gauze covering across the bottom of the shell, a coniform distributer within the shell, attached thereto at its lower edge and provided with gauze-covered apertures and a liquid-supply and an air-supply above 100 the distributer, substantially as set forth.

5. A device for vaporizing liquids, comprising an outer casing, a downwardly-extending shell therein, a gauze covering across the bottom of the shell, a coniform distributer within the shell attached thereto at its lower edge, 105 a liquid and an air supply above the distributer, an outlet-opening, and air-diluting openings through the shell, substantially as set forth. 110

6. A device for vaporizing liquids, comprising an outer casing, a downwardly-extending shell therein, a gauze covering across the bottom of the shell, a coniform distributer within the shell attached thereto at its lower edge, 115 a liquid and air supply above the distributer, an outlet-opening, and air-diluting openings through the shell, with means for regulating the supply therethrough, substantially as set forth. 120

7. A device for vaporizing liquids comprising an outer casing, a downwardly-extending shell therein, a gauze covering across the bottom of the shell, a coniform distributer within the shell attached thereto at its lower edge, 125 a liquid and an air supply above the distributer, an outlet-opening, and a drain-cock, substantially as set forth.

8. A device for vaporizing liquids comprising an outer casing, a downwardly-extending 130 shell therein, a gauze covering the bottom of the shell, a coniform distributer within the shell attached thereto at its lower edge, a valve-controlled liquid-supply above the dis-

tributer with a conduit leading thereto, air-supply openings leading to the interior of the shell, and an outlet-opening in the case, substantially as set forth.

5 9. A device for vaporizing liquids comprising an outer casing, a downwardly-extending shell therein, a coniform distributer within the shell attached thereto at its lower edge and provided with gauze-covered openings, a 10 liquid-supply and an air-supply above the distributer, and an outlet-opening in the case, substantially as set forth.

10 10. A device for vaporizing liquids comprising an outer casing, a downwardly-extending shell therein, a gauze covering the bottom of the shell, a distributer within the shell attached thereto at its lower edge, a liquid-supply and an air-supply above the distributer, and an outlet-opening in the case.

15 11. A device for vaporizing liquids comprising an outer case, a downwardly-extending shell therein, a space intervening between

the case and shell, a gauze covering the bottom of the shell, a distributer attached to the lower edge of the shell adapted to deliver the 25 liquid in a thin film upon the gauze, and an outlet-opening in the side of the case.

12. A device for vaporizing liquids comprising an outer case, a downwardly-extending shell therein, a space intervening between 30 the case and the shell, a gauze covering the bottom of the shell, a distributer attached to the lower edge of the shell adapted to deliver the liquid in a thin film upon the gauze, air-diluting openings leading into the intervening space, and an outlet-opening in the side of the case.

In testimony whereof I affix my signature in presence of two witnesses.
